DEVICE FOR RELEASABLY SECURING PLATES OR TOOLS TO PLATEN PRESSES

Henri Bobst and Josef Küry, Lausanne, Switzerland, assignors to J. Bobst & Fils, S. A., Prilly, Switzerland, a corporation of Switzerland

Original application September 17, 1941, Serial No. 411,145. Divided and this application December 27, 1943, Serial No. 515,752. In Switzerland October 9, 1940

2 Claims. (Cl. 101—390)

This application forms a division of our application Serial No. 411,145, filed September 17, 1941.

This application forms a division of Patent No. 2,353,215.

This invention relates to devices for releasably securing stereotype printing plates to the platen of a printing press or tools to the platen of a cutting press.

To locate and hold the plates in properly registered position on the platen, it has been customary to employ a frame for holding the plate, said frame being secured to the platen by means of wedges and screws. Due, however, to the time occupied in applying and removing these wedges and screws, particularly as this may have to be done quite frequently, such an arrangement has obvious inconveniences.

It is an object of the present invention to provide a device by which securing or releasing of the plates or tools to the platen may be effected in considerably less time than with previous arrangements.

The device in accordance with the invention comprises a frame for holding the plates or tools and means for clamping said frame at opposite edges thereof to the platen, the clamping means at one edge including means operable to press the frame against the platen and means operable correctly to register and hold the frame against lateral movement parallel to said edge, and the clamping means at the opposite edge being operable to press the frame towards the other clamping means, and actuating means at each edge of the frame common to all of the clamping means at that edge.

In order that the invention may be clearly understood and readily carried into effect, the same will hereinafter be more fully described with reference to the accompanying drawing, in which:

Fig. 1 is a vertical section of a press platen illustrating a preferred embodiment of frame and securing means therefore according to the invention;

Fig. 2 is a horizontal section on line II—II of Fig. 1; and

Figs. 3, 4 and 5 are detail sectional views on an enlarged scale of parts of the frame securing means of Figs. 1 and 2.

Referring now to the drawing, 1 designates a rectangular frame for holding cutting tools against the plane supporting face 2 of a platen 3, the plate and its arrangement within the frame forming no part of the invention and therefore

being omitted from the drawing. Arranged parallel to opposite ends of the platen are two shafts 4, 4a which are parallel to the adjacent edges of the frame and are journalled in suitable bearings (not shown) in the press frame as by means of eccentric discs or collars 5, 5a rigid with said shafts, the angular position of the shafts being controlled by handles 6, 6a. Pivotedly mounted on each shaft is a plurality of links 7, 7a, the free end of each link being angularly bent and apertured to slide over a rod about which is coiled a preferably powerful spring 12 which at one end abuts against the bent end of the link and is held at the other end by a nut threaded on the rod. By rocking the shafts 4, 4a through the intermediary of the handles 6, 6a, the links 7, 7a may be raised, as shown in Fig. 1, the springs 12 thus tending to raise the rods associated with said links.

As will be seen from Fig. 2, two link-and-rod clamping devices or assemblies and an intermediate registering device are provided at the left-hand end of the platen and two such devices or assemblies at the right-hand end. The rods 8 and 9 of the two outermost of said devices at the left-hand end are formed at their outer ends with hooks 10 (see also Fig. 4) which in the operative position are arranged to engage beneath a lip or flange 11 provided on the corresponding end of the frame 1, and upon actuation of the handle 6 to raise the shaft 4 the springs 12 associated with the rods 8, 9 will cause the hooks 10 of said rods to press the frame tightly against the face 2 of the platen. The rod 13 of the intermediate registering device is also formed at its outer end with a hook 14 (see also Fig. 3) the purpose of which is to engage within a recess 15 formed in the lip or flange 11, thereby in its operative position serving correctly to locate the frame laterally with respect to the platen and to hold it against lateral movement. The hook 14 and the notch 15 may be of trapezoidal shape, each being narrower at its upper end than at its lower end, in order to facilitate proper lateral positioning of the plate relatively to the platen.

Each of the rods 19 of the two clamping devices or assemblies at the right-hand end of the platen is formed with a wedge-shaped enlargement 20 (see also Fig. 5) the inclined face of which is arranged to co-operate with a correspondingly inclined face at the right-hand end of the frame. Upon actuation of the shaft 4a to raise the links 7a, the springs 12 cause the wedge-shaped ends 20 of the rods 19 to engage

the inclined face of the frame, thereby pressing the press firmly into engagement with the face 2 of the platen and also longitudinally in the direction of the arrow 16 (Fig. 2). As will be seen from Fig. 1 the rods 8, 9, 13 and 19 are guided in apertures in the platen so that they are held against movement other than in an axial direction. Thus the wedging action of the co-operating inclined faces of the rods 19 and the frame causes the latter to be moved towards the left into abutting engagement with the lower ends of the rods 8, 9 and 13 or with, for example, a machined, depending face at the left-hand end of the platen.

From the foregoing it will be understood that in the operative position of the clamping devices or assemblies, the frame will be pressed at opposite ends firmly against the supporting surface 2 of the platen and will also be secured against movement either laterally or longitudinally of the platen. To remove the frame, the shafts 4, 4a are rocked to lower the links and relax the pressure of the springs 12 on the rods, the latter allowing one end of the frame to drop on to, for example, a ledge (not shown) rigid with the platen and extending laterally thereof between the lower ends of the rods 8, 13 and 9, and the other end of the frame to drop on to a ledge or projection 17 extending inwardly beneath the right-hand end of the frame. The frame can then be slid laterally from beneath the platen in the direction of the arrow 18, or in a direction opposite thereto. To attach the frame to the platen, the foregoing sequence of operations is reversed, the frame being slid laterally into position beneath the platen and the shafts 4, 4a then being rocked to raise the links, thereby engaging the lower ends against the frame as hereinbefore described.

Any other appropriate means for imparting

lifting movement to the clamping devices may be employed in place of the eccentrics 5, 5a. Furthermore, such lifting means could be combined to actuate both sets of clamping devices simultaneously so as to secure or release the frame by a single operation. Finally, the number of clamping devices employed is not necessarily limited to that previously described.

What we claim is:

10. 1. A device for releasably securing printing plates or tools to the platen of printing respectively cutting presses comprising a frame for holding the plate and means for clamping said frame at opposite edges thereof to the platen, the clamping means at one edge including a rod connected by a spring to an actuating link, the said rod having a hook at one end engageable in the operative position with a lip extending from the frame in order to press the said frame against the platen and a rod connected by a spring to an actuating link and having a hook at one end engageable in the operative position within a recess in the edge of the frame in order to register and hold the frame against lateral movement parallel to said edge, and the clamping means at the opposite edge being operable to press the frame towards the other clamping means, and actuating means at each edge of the frame common to all of the clamping means at that edge.
15. 2. A device for releasably securing printing plates or tools to the platen of printing respectively cutting presses according to claim 1 wherein in the links are connected to a pair of shafts parallel to the opposite edges of the frame, said shafts each having eccentric bearing discs secured thereto.
20. 30. 35.
